YARN-CHANGING MECHANISM FOR CIRCULAR-KNITTING MACHINES

Application filed June 19, 1925. Serial No. 38,162.

One of the objects of my invention is to provide simplified mechanism for changing yarn in a circular knitting machine. Another object of my invention is to adapt such mechanism to a plural-feed or multiple-feed machine so that when the needles, in their movement of rotation, pass any one of the yarn feeds, any yarn finger of such feed may be moved into action and any yarn finger of such feed that is in action may be moved out of action.

The above objects are accomplished by means of the mechanism hereinafter described, which embodies my invention in its preferred form and which is illustrated in the accompanying drawings, in which—

Fig. 1 is a vertical central view through the machine frame.

Fig. 2 is a vertical sectional view through a part of the needle cylinder, cam cylinder, dial, dial cap, and the rotatable cams for operating the yarn-changing devices, and showing a set of yarn-changing devices and its corresponding selector.

Fig. 3 is a plan view of the yarn fingers and retainers.

Fig. 4 is a plan view of the rotatable cams.

Fig. 5 is a vertical section taken on line 5—5 of Fig. 4 showing the rotatable cams, one of the selectors and the lower part of a set of yarn finger actuating slides.

Fig. 6 is a section view, similar to Fig. 5 but taken on line 6—6 of Fig. 4, showing one of the rotatable cams in operating position.

Fig. 7 is an elevation of the clamp and cutter.

Fig. 8 is a perspective view of the clamp and cutter associated with a part of the cylinder needles and dial needles.

Fig. 9 is a plan view of the pattern mechanism and its connections with the selectors.

Fig. 10 is a plan view of the pattern chains, its actuating means and the devices immediately actuated thereby.

Fig. 11 is a side elevation of the construction shown in Fig. 10.

Fig. 12 is a side view showing the application of my invention, in a modified form, to a single feed hosiery machine.

Fig. 13 is a plan view of the cam disc carrying the yarn finger actuating cams that may be employed in said modified form of my invention.

The machine (see Fig. 1) comprises a stationary frame *a*, to which the cam ring *b* and the dial cap *f* are secured, and a revolvable frame *c* carrying the needle cylinder *d* and the needle dial *e*. The cylinder *d*, the dial *e* and the frame *c* are given a movement of rotation by the engagement of a pinion *h* with a rack *g* on cylinder *d*. Cylinder *d* carries the vertical needles *i* (see Fig. 8). Dial *e* carries the radial needles *j*. Cam ring *b* carries the cams (not shown) for actuating the cylinder needles *i*. Dial cap *f* carries the cams (not shown) for actuating the dial needles.

On a bracket *k* mounted on cam ring *b* is a shaft *m* on which are pivotally and independently mounted four yarn fingers or yarn carriers 1, 2, 3 and 4 (see Figs. 2 and 3). There may be any desired number of yarn carriers in a set. There may be a single set of yarn fingers or any desired number of sets of yarn fingers, dependent on whether the machine is a single-feed machine or a plural-feed machine. All the objects of my invention can be accomplished only on a plural-feed machine. In the embodiment of the invention herein shown, I have provided four sets of yarn fingers.

Between each set of yarn fingers 1, 2, 3 and 4 and the needles *i* is a yarn guide plate 100 having a deep recess 101 through which the yarn travels. This yarn guide, which is a well known contrivance, serves to guide the yarn to the needles.

Each yarn finger is under the tension of a spring *n*, which tends to hold it in a raised position (out of action). Fingers 1, 3 and 4 are shown in such position in Fig. 2. By means of slides 11, 12, 13 and 14, the four fingers respectively are capable of being swung down into operative position. This is accomplished by an upward movement of the slides. The slides and fingers constitute the yarn-changing devices.

On a shaft *o*, secured to bracket *k*, are four yarn finger retainers, or detents, 21, 100

22, 23, and 24, which are adapted to engage the respective yarn fingers and hold them down in operative position after their actuating slides have receded. These detents 5 may operate by gravity, but I prefer to actuate each detent by a spring p . To allow the yarn fingers to be held down by their respective detents, each finger is provided with a rear shoulder r , back of which its 10 detent drops. When the detents are raised, any finger that is down in operative position and that is not held down by its corresponding slide is free to swing up. Each finger is also provided with a front shoulder s , back of which its detent drops when 15 the finger swings up, so as to limit the extent of its upward movement; it being desirable that each finger shall be raised a definite distance, and that the several fingers 20 shall be raised to different levels, so that the threads shall lead therefrom to the clamp at different angles and thereby avoid the possibility of entangling one thread with another.

25 The following means is provided to raise the detents 21, 22, 23 and 24. Pivoted on shaft o is a lever t carrying a cross-pin u underlying the detents. A rod v is slideable vertically in guides in bracket k , and when 30 lifted, lifts lever t and pin u , thereby lifting all the detents and releasing all the yarn carriers.

Slides 11, 12, 13 and 14, which respectively lift yarn fingers 1, 2, 3 and 4, are 35 respectively actuated by cams 31, 32, 33 and 34 which rotate bodily with the needle cylinder d and are also pivoted thereon at w (see Figs. 4 and 5). There is a single set of such cams for operating all four sets of 40 slides. The slides are provided with tail pieces which are arranged at different distances from the axis of rotation of the needle cylinder. The four cams specified are arranged at correspondingly different 45 distances from the center of rotation, so that the four slides are in the respective paths of travel of the four cams. The four slides and their respective tail pieces are also arranged one in advance of another and the 50 four cams have their respective actuating surfaces one in advance of the other (see Figs. 4 and 5), so that one slide of a set is adapted, when actuated, to be actuated at the same point in the travel of the needle 55 cylinder as any of the other slides.

When any slide of a set is actuated by its cam, the latter also actuates a cam x (also pivoted on the needle cylinder at w) by engaging a cross pin y carried by the cam x . 60 Cam x is arranged nearer the axis of rotation than the nearest of the other cams. Rod v is in line of travel of cam x , and is operated thereby to lift lever t and pin u and thereby lift all the detents 21, 22, 23 and 24, as above described.

It will be observed, from an inspection of Figs. 4 and 5, that while cam x is slightly in advance of the nearest other cam, rod v is somewhat further in advance of the nearest slide, so that a slide is engaged by its cam a little before rod v is engaged by cam x . The four cams 31, 32, 33 and 34 are, however, of such greater length than cam x that the latter rides beyond rod v just before any of the cams that have lifted a slide ride beyond and release such slide. 75

Before proceeding with a description of the remainder of the machine, a brief description will be given of the operation of the yarn carriers by the mechanism described. 80

Let it be assumed that yarn finger 1 of a given set is down in operative position and delivering yarn to the needles, that yarn fingers 2, 3 and 4 of the same set are lifted out of action, and that cams 31, 32, 33 and 34, which are rotating with the needle cylinder, have not yet reached the slides for operating these fingers. In these positions of the yarn fingers, all their actuating slides 90 11, 12, 13 and 14 are down, detent 21 engages the rear shoulder r of yarn finger 1 (thus holding it down in action), and detents 22, 23 and 24 engage the front shoulders s of fingers 2, 3 and 4, which are held up out 95 of action by their respective springs n . Let it be further assumed that it is desired to lift out of action yarn finger 1 and swing down into action yarn finger 2. To accomplish this cam 32 is lifted (by means to be hereinafter described) on its pivot w as it approaches the tail piece on slide 12. In its lifting movement it engages pin y and lifts cam x . Cam 32 first engages and lifts 100 slide 12, which engages yarn finger 2 and swings it down into position to deliver yarn to the needles. In this movement retainer 22 is lifted out of notch s and drops into notch r . For a very short period of time 105 after yarn finger 2 is moved down into operative position, yarn finger 1 remains in operative position, because, as hereinbefore stated, although cam x lifts with cam 32, rod v is engaged by cam x a little after slide 12 is engaged by cam 32. As soon as cam x lifts rod v , all the detents 21, 22, 23, and 24 are lifted. Yarn finger 1 is thereupon lifted 110 out of action by its actuating spring n . (Its lifting movement, however, is limited by the contact of its tail piece with its actuating slide 11.) Yarn finger 2, however, continues to be held down by its actuating slide 12, which continues to be held up by its actuating cam 32. Before cam 32 rides 115 from under slide 12, cam x rides from under rod v , thereby allowing lever t , rod u and all the detents 21, 22, 23 and 24 to drop. Detents 21, 23 and 24 drop back of the front shoulders s of yarn fingers 1, 3 and 4, while 120 detent 22 drops back of the rear shoulder r

130

of finger 2. Very shortly thereafter, cam 32 rides beyond slide 12, and the latter drops, but finger 2 continues to be held in yarn feeding position by the engagement of detent 22 with its rear shoulder.

Thus, one yarn is withdrawn from the needles, while another yarn is introduced to the needles. It is obvious that any yarn carrier that is out of action may be moved into action, and that at the same time any yarn carrier that is in action may be moved out of action; and also that any yarn carrier that is in action may be maintained in action and that any yarn carrier that is out of action may be maintained out of action.

There should be a clamp and cutter, or some equivalent mechanism, that is operated to clamp and cut the yarn at the time that its finger is moved out of action. Any appropriate mechanism for this purpose may be used. A workable contrivance is shown in Figs. 7 and 8.

The cutter may comprise a fixed blade 41 (secured to a bracket 40 mounted on the dial cap *f*) and a movable blade 42, the latter forming one arm of a bell-crank lever pivotally mounted on bracket 40. The other arm 43 of the bell crank is in line of movement of the outer end of lever *t* when the latter is swung up by the actuation of rod *v* by cam *x*. Pivotally mounted on bracket 40 is another bell-crank lever, one arm 44 of which extends over arm 43, while the other arm 45 of which acts to clamp the yarn between it and the wall of bracket 40. A spring 46 holds arm 44 against arm 43.

In the yarn-changing operation hereinbefore described, the action of cam *x* on rod *v* and lever *t* lifts arm 43, thereby causing blade 42 to recede from blade 41 (opening the cutter) and causing clamp 45 to recede from bracket 40 (opening the clamp). At the same time, the yarn finger that is moved up out of action draws its yarn between the clamping members and also between the blades of the cutter. As soon as cam *x* recedes from rod *v*, lever *t* drops, and spring 46 closes the clamp on the yarn and then, by reason of the engagement of arm 44 with arm 43, closes the cutter and severs the yarn.

There may be secured to the hub of bell crank lever 42, 43 an arm 47 having a hooked end which, as said bell crank swings, engages the thread that is withdrawn from action and carries it up between the clamping members.

The selective operation of cams 31, 32, 33 and 34 is controlled by a non-rotatable cam-selecting cam, or selector, 50 (see Figs. 2, 5 and 6) which is carried by a longitudinally movable and radially extending pair of rods 51 slidable in a bracket 52 depending from the stationary cam ring *b*. Selector 50 may be shifted into five different positions, in one of which it is out of alignment with all the

cams and in any other of which it is in alignment with one or the other of the cams. When selector 50 is in alignment with any particular cam, the selector, in the rotation of such cam, actuates it, thereby causing the cam to actuate the corresponding yarn changing devices; also actuating cam *x*, thereby, through rod *v*, lever *t* and pin *u*, lifting all the detents and releasing all the yarn fingers except the one that has just been moved into yarn feeding position and is being held in that position by its slide; all as hereinbefore described.

When selector 50 is moved out of alignment with all the cams 31, 32, 33 and 34, no actuation of any of the yarn fingers or detents occurs. Hence, any yarn finger that is in action remains in action and such yarn fingers as are out of action remain out of action. In other words, the pattern of the fabric remains unchanged.

Each of the four sets of yarn-changing devices is operable (through the medium of rotatable cams 31, 32, 33 and 34) by its own special selector 50. There are therefore four of these selectors, each having its own actuating rods 51 carrying a block 53. Two of the blocks 53 (see Fig. 9) are operable by bell crank levers 54, 54, which, through links 55, 55, are connected to the long arms of bell crank levers 56, 56, the short arms of which carry rollers 57, 57. The blocks 53 on the other two pairs of rods 51 have a pin and slot connection with pivoted levers 58, 58, having arms carrying rollers 59, 59. The four rollers, 57, 57, 59, 59 rest respectively against projections on the ends of four levers 60 (see Figs. 10 and 11) swingable on a common shaft secured to a bracket 62 on cam ring *b*. The four levers 60 carry on their ends rollers 61, which are respectively in line of travel of lugs on four pattern chains 71, 72, 73 and 74, all mounted on sprockets driven by a common shaft 75 turnable in bearings in bracket 62. The pattern shaft has secured to it a ratchet 76, which is intermittently operable by a push pawl 77 depending from an arm 79 secured to a shaft 80 turnable in bracket 62. To shaft 80 is secured an arm 81 having on its end a roller 82 in the path of travel of a cam 84 secured to the revolvable frame *c* carrying the needle cylinder *d*. A holding pawl 85 pivoted on bracket 62 holds ratchet 76 from slipping back after it has been actuated by pawl 77. A spring 78 maintains pawl 77, and a spring 86 maintains holding pawl 85, in operative relation with ratchet 76. A spring 83 holds arm 81 in the path of travel of cam 84, but yields to allow the cam to operate the arm.

It will be understood that the invention is applicable to a single feed machine on which provision for changes of yarn is desired, as, for example, there need be only a single pattern chain, a single selector 50, 130

a single mechanical connection between the pattern chain and selector 50, a single set of slides 11, 12, 13, 14, a single set of yarn fingers 1, 2, 3, 4, and a single set of detents 21, 22, 23, 24; and the yarn fingers 5 may be two or more in number with a corresponding number of detents, slides, and 10 slide-actuating cams. Such yarn-changing mechanism presents distinct advantages in respect to simplicity of construction and 15 certainty of operation. In such a machine, in place of a single selector, it would be preferable to substitute a series of cams carried or operable by a pattern chain, disc or 20 drum.

One mode of applying the invention to a single feed machine is shown in Figs. 12 and 13. The machine may be the type of hosiery machine shown, for example, in the Harry A. Houseman Patent No. 1,207,757, dated December 12, 1916, in which 90 is the frame of the machine and 91 the bed plate for the needle cylinder 92, cam ring 93 and appurtenant mechanism. The yarn fingers, 25 finger retainers, cam actuating slides and the slidable vertical rod for actuating the retainers and the clamp and cutter may be the same as heretofore described and as shown best in Fig. 2. Instead of providing 30 the series of cams 31, 32, 33 and 34, shown in Fig. 2, which rotate with the needle cylinder, I provide a series of cams 310, 320, 330 and 340 and locate them on an intermittently rotatable cam disc 94, similar in 35 structure and operation to that shown in said patent. Associated with the several cams 310, 320, 330 and 340 are cams ω' , which correspond in function to the cam ω of Fig. 2 and actuate a rod v , which corresponds to the rod v of Fig. 2. Of course, 40 there may be any number and arrangement of yarn finger actuating cams on the cam disc. For example, if it is desired to simultaneously move into action two yarn fingers, two cams are arranged side by side on 45 the pattern disc, as illustrated in Fig. 13.

By means of my invention, a wide variety of patterns may be produced by arranging the lugs or cams on the pattern device in any predetermined way. Thus, referring to the first described embodiment of my invention, if it be desired to produce circumferential stripes of different widths, the invention provides means for producing such stripes in any color and of any width. If, for example, it is desired to produce a blue stripe having the width of a single course, a lug on any desired pattern chain is so positioned that, at the stage of the knitting 55 at which the blue yarn is to be thrown in, such lug is caused to shift the corresponding cam actuator 50 that will operate the particular rotatable cam that operates the particular slide that operates the finger that carries the blue yarn. It will be understood 60

that the distance to which selector 50 is shifted depends on the height of the lug on the pattern chain. A low lug effects a shift of selector 50 so that it operates cam 34, which is most distant from the axis of rotation. A lug somewhat higher shifts selector 50 so that it operates cam 33. A lug still higher shifts selector 50 so that it operates cam 32. A high lug shifts selector 50 so that it operates cam 31. It will also be understood that the finger carrying the blue yarn of only one of the four sets of yarn fingers is operated, namely, that set of yarn fingers which is positioned above the particular selector 50 that is shifted as described. The three fingers carrying the blue yarn of the other three sets are not operated, because their corresponding selectors 50 are not positioned to actuate the corresponding slide actuating cam. 70 75 80

If a double circumferential blue stripe is desired, lugs of the same height on two adjacent pattern chains are caused to simultaneously similarly shift two adjacent cam selectors 50; and hence two corresponding yarn fingers, one of one set and one of an adjacent set, are moved into action, thereby causing two successive blue courses to be knit into the fabric. 85

If four successive blue courses are to be knitted, lugs of the same height on all four pattern chains are caused to simultaneously similarly shift all four selectors 50. 90

If it is desired to knit alternate courses of (say) blue and white, lugs of the same height on alternate pattern chains are caused to simultaneously shift diametrically opposite selectors 50 to similar positions, while two other lugs of the same height as each other, but of a height different from the other two lugs, are caused to shift the other two diametrically opposite selectors 50 to positions similar to each other but different from the positions to which the two first mentioned selectors are shifted. 100 105 110

It will thus be understood that a yarn of any color may be caused to knit any particular course or number of courses of the fabric. 110

If it be desired that any particular yarn carrier shall remain in action for a number of courses, the corresponding cam selector 50 may be allowed to remain in its operative position; or, preferably, such cam selector may be shifted back to neutral position (that is, where it aligns with none of the cams 31, 32, 33, 34) and the detent corresponding to such yarn carrier will maintain it in yarn feeding position. 115 120

While the invention is described as applicable to a rotating needle cylinder and dial and rotating yarn-changing actuating cams, and a non-rotatable cam ring and dial cap and non-rotatable yarn fingers and selectors, it will be understood that either 125 130

of these two groups of mechanisms may be 5 rotatable and the other non-rotatable, as is well understood in the art, and that the expressions "rotatable" and "non-rotatable", although applicable in an absolute sense, to the embodiment of the invention shown, are used in a relative sense in the claims.

It will also be understood that while I have illustrated the invention as applied to 10 a dial machine, it is capable of application to a cylinder machine, or one in which there is a single circumferential bank of needles instead of two banks extending respectively vertically and radially. No change in 15 the mechanism would be required to make this adaptation.

Where, in the claims, I refer to elements, such as the cams 31, 32, 33, 34 and α , as being rotatable, I intend it to be understood 20 that they partake of the relative movement of rotation of the needle cylinder, and in referring to elements, such as the yarn fingers, their actuators and the selectors 50, as being non-rotatable, I intend it to be understood 25 that, like the cams 31, 32, 33, 34 and α , they do not partake of the relative movement of rotation of the needle cylinder.

Having now fully described my invention, what I claim and desire to protect 30 by Letters Patent is:

1. In a circular knitting machine, the combination with a rotatable needle cylinder, of a set of yarn fingers independently movable into operative and inoperative 35 positions, springs adapted to move the yarn fingers into one position, independently operable yarn finger actuators, one for each yarn finger, adapted to move the yarn fingers into the other position, retainers 40 adapted to respectively engage the yarn fingers that have been moved into the second position and hold them in such position, each retainer being independently movable in the movement of a yarn finger 45 from the first to the second position, retainer-withdrawing means adapted to effect the release by a retainer of a yarn finger in the second position to allow it to be moved into the first position by its spring, a set of 50 independently operable devices, one for each yarn finger actuator, adapted to actuate the respective yarn finger actuators, selecting means adapted to be shifted into different 55 positions to selectively actuate any of the said devices, another device adapted to operate the retainer withdrawing means, and pattern mechanism adapted to effect the movement of the selecting means into said different positions and synchronously therewith effect the operation of the device for actuating the retainer withdrawing means: 60
2. In a circular knitting machine, the combination with a rotatable needle cylinder, of a set of yarn fingers independently mov- 65 able in opposite directions into operative and inoperative positions, springs adapted to independently move the respective yarn fingers in one direction, independently operable yarn finger actuators adapted to move the respective yarn fingers in the other direction, retainers adapted to hold the respective fingers in one position against the tension of their springs, each retainer being independently movable in the movement of a yarn carrier toward the last named position, a set of independently operable devices adapted to actuate the respective yarn finger actuators, means independent of the yarn finger actuators to temporarily withdraw from holding position any retainer that has been holding a yarn finger to allow the latter to be operated by its spring, a single selector adapted to be shifted into positions to actuate any of said devices and in such actuation to operate said retainer-withdrawal means, and pattern mechanism adapted to move the selector into the different positions required to actuate said devices.
3. In a circular knitting machine, the combination with a rotatable needle cylinder, of a set of independently movable yarn fingers, springs tending to withdraw the respective yarn fingers out of yarn-feeding position, means to selectively move the respective yarn fingers into yarn-feeding position, retainers adapted to hold the respective yarn fingers in yarn-feeding position, each retainer being independently movable in the movement of a yarn finger toward yarn-feeding position, means adapted, after the movement of a yarn finger into yarn-feeding position, to operate all the retainers to allow any other yarn finger that is in yarn-feeding position to be withdrawn from such position by its spring and to release said retainers to cause the yarn finger that has been last moved into said position to be held in such position by its retainer.
4. In a circular knitting machine, the combination with a rotatable needle cylinder, of a set of independently movable yarn fingers, springs tending to move the respective yarn fingers out of yarn-feeding position, a set of independently operable non-rotatable yarn finger actuators adapted to move the respective yarn fingers into yarn-feeding position, a set of retainers adapted to hold the respective yarn fingers in yarn-feeding position, each retainer being independently movable in the movement of a yarn finger toward yarn-feeding position, means to selectively actuate the yarn finger actuators, and means adapted, after the selective movement of a yarn finger into yarn-feeding position, to withdraw all the retainers to allow any yarn finger in operative position to be withdrawn from operative position by its spring and to return said retainers to cause any yarn finger that has

been moved into operative position by its actuator to be held in such position by its retainer.

5. In a circular knitting machine, the combination with a rotatable needle cylinder, of a set of independently movable yarn fingers, springs tending to withdraw the respective yarn fingers out of yarn-feeding position, means to selectively move the respective yarn fingers into yarn-feeding position, retainers adapted to hold the respective yarn fingers in yarn-feeding position, springs adapted to move and hold the respective retainers in holding position, each retainer being independently movable in the movement of a yarn finger toward yarn-feeding position, and means adapted, after the selective movement of a yarn finger into yarn-feeding position, to withdraw all the retainers, against the action of their springs, to allow any yarn carrier finger in operative position to be withdrawn from operative position by its spring and to release said retainers to allow one of them to be actuated by its spring to hold in yarn-feeding position any yarn finger that has been moved into such position.

6. In a circular knitting machine, the combination with a rotatable needle cylinder, of a set of yarn fingers adapted when in operative position, to feed yarn to the needles and independently movable in opposite directions into operative and inoperative positions, springs adapted to independently move the respective yarn fingers in one direction, independent yarn fingers actuators adapted to move the respective yarn fingers in the other direction, retainers adapted to hold the respective yarn fingers in one position against the tension of their springs, each retainer being independently movable in the movement of its corresponding yarn finger in the last named direction springs tending to hold the retainers in holding position, devices, one for each yarn finger actuator, adapted to respectively operate the same, mechanism adapted synchronously with the operation of the yarn fingers in one direction, to temporarily withdraw all the retainers from holding position against the action of their springs, and means to independently and selectively operate said devices to bring them into operative relation with the respective finger actuators and to synchronously operate said retainer withdrawal mechanism.

7. In a circular knitting machine, the combination with a rotatable needle cylinder, of a set of independently movable yarn fingers, springs tending to withdraw the respective yarn fingers out of yarn-feeding position, cams, one for each yarn finger, adapted to selectively move the respective yarn fingers into yarn-feeding position, retainers adapted to hold the respective yarn

fingers in yarn-feeding position, each retainer being independently movable in the movement of the corresponding yarn finger into yarn-feeding position, a lever adapted when moved in one direction to withdraw all said retainers from holding position to allow any yarn finger in operative position to be withdrawn from such position by its spring and adapted when moved in the opposite direction to release all said retainers to allow any one of them to hold in yarn-feeding position any yarn finger that has been moved into such position, and a cam adapted to operate said lever synchronously with the actuation of a yarn finger by its corresponding cam.

8. In a circular knitting machine, the combination with a rotatable needle cylinder, of a set of non-rotatable independently movable yarn fingers, a set of independently operable non-rotatable yarn finger actuators adapted to move the respective fingers into yarn-feeding position, a set of independently operable cams rotatable with the needle cylinder and adapted to actuate the respective yarn finger actuators, non-rotatable selecting means adapted to be shifted into position to selectively actuate any of the rotatable cams, and pattern mechanism adapted to move the selecting means into any predetermined operative position.

9. In a circular knitting machine, the combination with a rotatable needle cylinder, of a set of non-rotatable independently movable yarn fingers, a set of independently operable non-rotatable yarn finger actuators adapted to move the respective fingers into yarn-feeding position, a set of independently operable cams rotatable with the needle cylinder and adapted to actuate the respective yarn finger actuators, non-rotatable selecting means adapted to be shifted into position to selectively actuate any of the rotatable cams, means, operable after the actuation of the selected cam and the corresponding yarn finger actuator and yarn finger, to effect a withdrawal from yarn-feeding position of any yarn finger that is in yarn-feeding position, and pattern mechanism adapted to move the selecting means into any predetermined operative position.

10. In a circular knitting machine, the combination with a rotatable needle cylinder, of a set of non-rotatable independently movable yarn fingers, a set of independently operable devices rotatable with the needle cylinder and adapted to move the respective fingers into and temporarily hold them in yarn-feeding position, finger retainers adapted to hold the respective yarn fingers in yarn-feeding position, non-rotatable selecting means adapted to be shifted into position to selectively operate the rotatable finger actuating devices, means, operable in the actuation of a finger-actu-

ating device, to withdraw from operative position any retainer that is holding its corresponding yarn finger in yarn-feeding position, means to move into operative position the retainer corresponding to the finger that is moved into yarn-feeding position by its corresponding rotatable device, and pattern mechanism adapted to move the selecting means into any of its operative 5 positions.

11. In a circular knitting machine, the combination with a rotatable needle cylinder, of a set of non-rotatable independently movable yarn fingers, a set of independently operable devices rotatable with the needle cylinder and adapted to move the respective fingers into and temporarily hold them in yarn-feeding position, retainers adapted to hold the respective yarn fingers in yarn-feeding position, non-rotatable selecting means adapted to be moved into position to selectively operate the finger-actuating devices, means, operable in the actuation of 15 a finger-actuating device, to withdraw from operative position all the finger retainers and to release them before the selectively operated rotatable finger-moving and holding device releases its yarn finger, and pattern mechanism adapted to move the selecting means into any of its actuating 20 positions.

12. In a circular knitting machine, the combination with a rotatable needle cylinder, of a set of non-rotatable independently movable yarn fingers, a set of independently operable devices rotatable with the needle cylinder and adapted to move the respective fingers into and temporarily hold them in yarn-feeding position, finger retainers 25 adapted to hold the respective yarn fingers in yarn-feeding position, means to withdraw from operative position any retainer that is holding its corresponding yarn finger in yarn-feeding position, means operable by 30 any of said finger-moving and holding devices, adapted to so actuate said retainer-withdrawing means and to release said retainer-withdrawing means before the actuated finger-moving and holding device releases its respective yarn finger, non-rotatable selecting means adapted to be moved 35 into position to selectively operate the finger-moving and holding devices, and pattern mechanism adapted to shift the selecting means into any of its operative positions.

13. In a circular knitting machine, the combination with a rotatable needle cylinder, of a set of non-rotatable independently movable yarn fingers, a set of non-rotatable independently operable slides adapted to move the respective fingers into yarn-feeding position, springs tending to withdraw the yarn fingers from yarn-feeding position, a set of independently operable 40 cams rotatable with the needle cylinder and

adapted to actuate the respective slides, non-rotatable selecting means adapted to be moved into position to selectively actuate any of said cams, and pattern mechanism adapted to move the selecting means into 45 any predetermined operative position.

14. In a circular knitting machine, the combination with a rotatable needle cylinder, of a set of non-rotatable independently movable yarn fingers, a set of non-rotatable independently operable slides adapted to move the respective fingers into yarn-feeding position, springs tending to withdraw the yarn fingers from yarn-feeding position, a set of independently operable cams 50 rotatable with the needle cylinder and adapted to move the respective slides into position to move and temporarily hold the respective yarn fingers in yarn-feeding position, retainers adapted to retain the respective yarn fingers in yarn-feeding position after they are released by their respective slides, non-rotatable selecting means adapted to be shifted into position to selectively actuate any of said cams, means operable by any of said cams to withdraw the 55 retainers from retaining position to allow any finger in yarn-feeding position to be withdrawn from such position, said retainers being freed from said withdrawal means to allow one of them to move into position to retain in yarn-feeding position the finger which is moved into yarn-feeding position by the cam and slide that are operated by the selecting means, and pattern mechanism 60 adapted to move the selecting means into any predetermined operative position.

15. In a circular knitting machine, the combination with a rotatable needle cylinder, of a set of non-rotatable independently movable yarn fingers, a set of non-rotatable independently operable slides adapted to move the respective fingers into yarn-feeding position, springs tending to withdraw the yarn fingers from yarn-feeding position, retainers adapted to hold the yarn fingers in yarn-feeding position against the action of their springs, a set of independently operable slide actuating cams 65 rotatable with the needle cylinder, a cam and connections therefrom to the retainers for moving the latter out of said retaining position, selecting means adapted to effect the successive operation of one of the first named cams and the last named cam to successively effect the movement of one of the fingers into yarn feeding position, allow another finger that has been in yarn feeding position to be moved out of action by its spring, and allow the retainer for the first named finger to operate to hold such finger in yarn feeding position, and pattern mechanism adapted to move the selecting means into different predetermined operative positions.

16. In a circular knitting machine, the combination with a rotatable needle cylinder, of a set of non-rotatable independently movable yarn fingers, a set of non-rotatable independently operable slides adapted to move the respective fingers into yarn-feeding position, springs tending to withdraw the yarn fingers from yarn-feeding position, a set of independently operable cams rotatable with the needle cylinder and

adapted to actuate the respective slides, non-rotatable selecting means adapted to be moved into position to selectively actuate any of said cams, and pattern mechanism adapted to move the selecting means into any predetermined operative position.

17. In a circular knitting machine, the combination with a rotatable needle cylinder, of a set of non-rotatable independently movable yarn fingers, a set of non-rotatable independently operable slides adapted to move the respective fingers into yarn-feeding position, springs tending to withdraw the yarn fingers from yarn-feeding position, retainers adapted to hold the yarn fingers in yarn-feeding position against the action of their springs, a set of independently operable slide actuating cams rotatable with the needle cylinder, a cam and connections therefrom to the retainers for moving the latter out of said retaining position, selecting means adapted to effect the successive operation of one of the first named cams and the last named cam to successively effect the movement of one of the fingers into yarn feeding position, allow another finger that has been in yarn feeding position to be moved out of action by its spring, and allow the retainer for the first named finger to operate to hold such finger in yarn feeding position, and pattern mechanism adapted to move the selecting means into different predetermined operative positions.

18. In a circular knitting machine, the combination with a rotatable needle cylinder, of a set of non-rotatable independently movable yarn fingers, a set of non-rotatable independently operable slides adapted to move the respective fingers into yarn-feeding position, springs tending to withdraw the yarn fingers from yarn-feeding position, a set of independently operable cams rotatable with the needle cylinder and

adapted to actuate the respective slides, non-rotatable selecting means adapted to be moved into position to selectively actuate any of said cams, and pattern mechanism adapted to move the selecting means into any predetermined operative position.

16. In a circular knitting machine, the combination with a rotatable needle cylinder, of a plurality of sets of non-rotatable yarn-changing devices, a set of cams rotatable with the needle cylinder and adapted to operate the respective yarn-changing devices of each set, a plurality of non-rotatable selecting means, one for each set of yarn-changing devices adapted to be moved into different positions to selectively operate the rotatable cams and thereby respectively operate the yarn-changing devices of the corresponding set, and separate pattern mechanism adapted to position each selecting means. 70
17. In a circular knitting machine, the combination with a rotatable needle cylinder, of a plurality of sets of non-rotatable yarn-changing devices, a plurality of non-rotatable selecting means, one for each set of yarn-changing devices, and each movable into different positions, pattern-controlled mechanism for independently positioning each selecting means, and common means rotatable with the needle cylinder and operable by all the selecting means and operable by each selecting means to actuate the corresponding yarn-changing devices in accordance with the position of such selecting means. 75
18. In a circular knitting machine, the combination with a rotatable needle cylinder, of a plurality of sets of non-rotatable independently movable yarn fingers, a set of independently operable devices rotatable with the needle cylinder and adapted to move the respective yarn fingers of each set into yarn-feeding position, a plurality of selecting means, one for each set of yarn fingers, adapted, in the rotation of said set of finger-moving devices, to selectively actuate the rotatable finger-moving devices and thereby selectively actuate the yarn fingers of the corresponding set, and pattern mechanism adapted to move the several selecting means independently and each of them into position to actuate any predetermined rotatable finger-moving device. 80
19. In a circular knitting machine, the combination with a rotatable needle cylinder, of a plurality of sets of non-rotatable independently movable yarn fingers, a plurality of sets of retainers, one set for each set of yarn fingers, adapted to hold the respective fingers in yarn-feeding position, a set of independently operable devices rotatable with the needle cylinder and adapted to move the respective yarn fingers of each set into yarn-feeding position and release the retainers of each set, and a plurality of selecting means, one for each set of yarn fingers and retainers, adapted, in the rotation of said set of finger-moving devices, to selectively actuate said devices and thereby selectively actuate the yarn fingers and release the retainers of the corresponding set, and pattern mechanism adapted to move the several selecting means independently and each of them into position to actuate any predetermined rotatable finger-moving device. 85
20. In a circular knitting machine, the combination with a rotatable needle cylinder, of a plurality of sets of non-rotatable independently movable yarn fingers, a plurality of sets of non-rotatable independently operable slides adapted to move the respective fingers of the corresponding sets of fingers into yarn-feeding position, springs tending to withdraw the yarn fingers from yarn-feeding position, a plurality of non-rotating selecting means, one for each set of slides, each of which is movable into positions to effect the selective operation of the respective slides of the corresponding set, cams rotatable with the needle cylinder and adapted in their rotation to be actuated by either of the selecting means that is positioned to control a given slide, and thereby actuate such slide, and pattern mechanism independently controlling the positioning of each selecting means. 90
21. In a circular knitting machine, the combination with a rotatable needle cylinder, of a plurality of sets of non-rotatable independently movable yarn fingers, a set of non-rotatable independently operable slides for each set of fingers, the slides of a set being adapted to move their corresponding fingers into, and temporarily hold them in, yarn-feeding position, springs tending to withdraw the yarn fingers from yarn-feeding position, a plurality of sets of non-rotatable retainers adapted to hold the respective fingers of the corresponding sets of fingers in the yarn-feeding positions into which they are moved by their slides, a plurality of non-rotatable selectors, one for each set of slides, each of which is movable into position to effect the selective operation of the respective slides of the corresponding set, a set of cams rotatable with the needle cylinder and adapted in their rotation to be actuated by either of the selectors that is positioned to effect the operation of a given slide and thereby actuate such slide, independent pattern mechanism controlling the positioning of each selector; mechanism associated with each set of retainers and adapted to lift and temporarily hold them out of the specified retaining position, and a cam rotatable with the needle cylinder and movable with the first named cams and adapted to operate said mechanism substantially concurrently with the operation of the slides, thereby withdrawing said retainers to allow a yarn carrier that has been in yarn-feeding position to be withdrawn and allowing the retainers to be repositioned to 95

hold in yarn-feeding position a yarn carrier that has been moved thereinto by a slide.

22. In a circular knitting machine, the combination with a rotatable needle cylinder, of a plurality of sets of non-rotatable yarn-changing devices, a set of cams rotatable with the needle cylinder and adapted to operate the yarn-changing devices of the several sets and also selectively operate the 10 yarn-changing devices of each set, a plurality of non-rotatable selectors, one for each set of yarn-changing devices, adapted to be moved into different positions to selectively operate the rotatable cams and thereby 15 selectively operate the yarn-changing devices of the corresponding set, separate pattern mechanisms adapted to position each selector, a non-rotatable clamp and cutter for each set of yarn-changing devices, and means 20 operable in the operation of any cam to actuate the clamp to hold the yarn that is withdrawn from feeding position and actuate the cutter to cut the yarn so held.

23. In a circular knitting machine, the 25 combination with a rotatable needle cylinder, of a plurality of sets of non-rotatable yarn-changing devices arranged at different points about the circumference of the needle cylinder, a plurality of non-rotatable selectors arranged in proximity to the respective 30 yarn-changing devices, common means rotatable with the needle cylinder and operable by all the selectors and operable by each selector to actuate the corresponding yarn-changing devices in accordance with the 35 position of the selector, selector-positioning means, one for each selector, and pattern chains corresponding in number to the selectors and located in proximity to one another 40 and controlling the operation of the respective selector-positioning means.

In testimony of which invention, I have hereunto set my hand, at Philadelphia, Pennsylvania, on this 17th day of June, 45 1925.

HAROLD E. HOUSEMAN.
